Silverton, Oreg. 97381

Filed Dec. 7, 1967, Ser. No. 9,679

Term of patent 14 years

Int. Cl. D17—03

U.S. Cl. D56—1

FIG. 1 is a front elevational view of a body of a stringed musical instrument, showing my new design, the rear being substantially a mirror image thereof;

FIG. 2 is a left side elevational view, the right side being substantially a mirror image thereof;

FIG. 3 is a bottom plan view thereof;

FIG. 4 is a left side view partly in cross-section taken on line 4—4 of FIG. 1 thereof; and

FIG. 5 is a right side view partly in cross-section taken on line 5—5 of FIG. 1 thereof.

I claim:

The ornamental design for the body of a stringed musical instrument, substantially as shown and described.
